Inventor Myrick Dudley

Attorneys J. J. & J. E. Bartell

UNITED STATES PATENT OFFICE.

MYRICK DUDLEY, OF LYNN, MASSACHUSETTS, ASSIGNOR OF TWO-THIRDS
TO IVORY B. HILL, OF SANDWICH, NEW HAMPSHIRE.

AUTOMATIC STREET-RAILWAY SWITCH.

piece *d* and pushing the end of the lever *D* under the block *N*, where it may rest. As this end of the lever *D* drops, the other end rises and raises with it the rod *G*, the cross-bar *F*, the arm *H*, and the arm *J*. The spring *f* keeps the cross-bar *F* pressing steadily upon the rest *K* when in use.

What I claim as my invention is—

1. A switch-rail consisting of a base, with an adjustable end pivoted to the base, so as to automatically raise the point above the level of the track, substantially as described.
2. The base *A'* of the switch-rail, in combination with the adjustable end *A'*, the stud *a'*, and the raised point *a*, substantially as described.
3. The arm *J*, in combination with the rod

G, lever *D*, and swivel-fulcrum *E*, substantially as described.

4. The arm *J*, in combination with the arm *H*, cross-bar *F*, and axle *O*, substantially as described.

5. The lever *D*, in combination with the cross-bar *F*, rest *K*, and axle-box *L*, substantially as described.

6. The switch-rail *A*, in combination with the arm *J*, cross-bar *F*, rod *G*, lever *D*, swivel-fulcrum *E*, block *N*, arm *H*, and rest *K*, substantially as described.
